GRAIN SEPARATING MACHINE

Filed Aug. 17, 1928 2 Sheets-Sheet 2

UNITED STATES PATENT OFFICE

WILLIAM THOMAS PIERCE, OF BIRLE, MANITOBA, CANADA

GRAIN SEPARATING MACHINE

Application filed August 17, 1928, Serial No. 300,354, and in Canada May 5, 1928.

The invention relates to improvements in grain separating machines and an object of the invention is to provide a machine which will effectively separate bearded grains from smooth faced grains and will discharge the separated grains at opposite ends of the machine.

A further object of the invention is to provide a machine utilizing rotatable cylindrical drums having their inner faces lined with a cloth or such like material presenting considerable nap and agitated troughs or chutes within the drums adapted to receive and discharge the bearded grains carried up by the drums and scraped therefrom by stationary scrapers provided.

A further object is to construct the machine so that it can be readily assembled and such that it will have considerable separating capacity.

A still further object is to construct the machine wherein the drums are mounted in a novel manner and wherein the chutes employed are suspended within the drums for reciprocating movement, such facilitating the travel of the grain within the chutes.

With the above more important objects in view, the invention consists essentially in the arrangement and construction of parts hereinafter more particularly described, reference being had to the accompanying drawings, in which:—

Fig. 1 is a view of the front end of the machine.

Fig. 2 is a view of the rear end of the machine.

Fig. 3 is a vertical sectional view longitudinally and centrally through the machine, certain parts being shown in side elevation.

Fig. 4 is a plan view of the front end of the machine.

In the drawings like characters of reference indicate corresponding parts in the several figures.

The machine frame comprises the customary corner legs 1 connected by suitably located end strips 2 and suitably located side strips 3, the end strips at the front end of the machine being somewhat closer together than those at the rear and the side strips be-

ing inclined as shown to connect the end strips. On the rear end of the machine, I mount a suitable grain receiving feed hopper 4 which is provided more or less centrally with a feed opening 5 controlled by a hand regulated sliding gate 6. The machine as herein shown embodies three similar rotatably mounted separating drums or cylinders but I wish it to be understood that a greater or less number of these could be used without departing from the spirit of the invention.

Within the upper part of the frame, I locate a pair of upper cylinders or drums 7 and 8 having open ends and of considerable diameter, the drums having their ends suitably reinforced by external ribs 9 and 10 and their interior walls lined with a cloth, carpet or such like lining 11 presenting a considerable nap. The drums are revolvably supported by three similar parallel rollers 12, 13 and 14 extending longitudinally of the machine and inclining upwardly from the front to the rear, the rollers being carried by shafts 15, 16, and 17 rotatably mounted in end bearings 18 carried by the centrally located end boards 2. The rollers are all provided adjoining the front end of the machine with comparatively deep outstanding flanges 19 and these flanges prevent the drums from end shifting forwardly. The drums actually ride the rollers and upon the rollers being rotated in a manner later described, the drums will be simultaneously rotated by frictional contact with the rollers.

Centrally underneath the upper pair of drums, I locate a similar lower drum or cylinder 20 provided with a nap lining and supported by two parallel inclining rollers 21 and 22 having the shafts 23 and 24 thereof rotatably mounted in suitable end bearings 25 carried by the end boards. It will be observed that the drum 20 is inclined in the opposite direction to the upper drums and that the lower rollers are provided with end flanges 26 to prevent the lower drum shifting towards the rear end of the machine.

Two similar feed spouts 27 and 28 are carried by the frame and are adapted to feed grain from the hopper into the rear or upper ends of the upper drums 7 and 8. A collect-

ing pan 29 carried by the frame underlies the forward ends of the cylinders 7 and 8 and two grain spouts 30 and 31 lead from this pan and discharge into the lower cylinder 20.

5 The rear end of the frame is supplied with a short stub shaft 32 on which I rotatably mount a chain wheel 33, the chain wheel being supplied with an operating handle or crank 34. The rear ends of the shafts 15, 16, 10 17, 23 and 24 are all supplied with similar chain wheels 35 and an endless chain 36 passes around these latter chain wheels 35 in a manner best shown in Figure 3, the arrangement being such that when the crank 15 34 is turned, the rollers are all simultaneously rotated and the cylinders are consequently turned.

Within each of the upper cylinders, I locate a grain chute 37 which grain chutes are inclined in the same direction as the cylinders and are supported there within for reciprocating movement. The front end of each chute is pivotally carried by a pair of downwardly extending side arms 38 and 39 which 20 have their lower end pivotally connected to a bracket 40 permanently secured centrally to an end board 2. The forward ends of the upper chutes are pivotally swung from a cross arm 41 carried by a vertical spindle 42, 25 the spindle having the ends thereof rotatably mounted in bearings 43 carried by the end boards. In the present instance, the ends of the cross arm are down turned and are passed rotatably through a cross strap 44 secured to 30 the end of the chute and beneath the cross strap, I place a washer 45 and a retaining pin 46.

The front end of the machine is supplied at one of the upper corners with a relatively 40 short spindle 47 rotatably carried by the frame and on the spindle, I mount a chain wheel 48 and a disc 49, the chain wheel being driven by a chain 50 operating over a further chain wheel 51 secured to the forward end of 45 the shaft 17. The disc carries an eccentric pin 52 which is connected by a pitman 53 to a crank 54 carried by the upper end of the spindle 42, the arrangement being such that the spindle is oscillated backwardly and forwardly in the rotation of the disc and the cross arm causes the reciprocation of the chutes 37.

The lower cylinder is also provided with a chute 55 which is inclined in the opposite 55 direction to the drum 20 and passes centrally therethrough. The rear end of the latter chute is pivotally attached to the horizontally disposed end 56 of an arm 57, the arm having the lower end pivotally attached at 58 to the lower end board 2. A vertical spindle 59 is rotatably carried in suitable bearings 60 mounted on the rear end boards of the frame and the spindle carries a crank arm 61 which pivotally supports the rear end of the lower 60 chute in the same manner as the upper chutes

are supported from the cross arm. The lower end of the spindle 42 and the upper end of the spindle 59 are both supplied with cranks 62 and 63 and the cranks are pivotally connected by a cross bar 64, the arrangement 70 being such that the lower chute is reciprocated simultaneously with the upper chutes.

In order to scrape or free the grains caught in the nap of the cylinder linings, I have provided stationary scrapers 65 herein shown 75 as rods passing longitudinally of the cylinders and contacting with the lining, the rods being suitably carried by the frame and being positioned so that they each overlie one side of the adjoining chute. The machine can be 80 driven by a belt if desired at which time, the crank 34 would be dispensed with and a pulley supplied for driving purposes.

When the machine is to be used, one adjusts the gate to feed the grain into the upper cylinders and drives the chain wheel 34 by rotating the crank. The rollers are all simultaneously rotated and effect the rotation of the drums in the same direction. The bearded grains and other small weed seeds and foreign material will be caught in the nap of the lining of the upper cylinders and will be carried up towards the scrapers whilst the non-bearded and free sliding grain seeds will 90 gravitate down the upper cylinders and will be discharged from the front ends thereof into the underlying pan 29. Those seeds which are carried up by the lining of the cylinders will fall down and be caught in the chutes 37, the scrapers serving to free such 95 grains from the nap. The material caught in the chutes will be passed out the forward end of the machine, their movement being facilitated by the reciprocation of the chutes. The grain caught in the pan 29 will be 100 discharged in the lower cylinder and here a further separation takes place, the free running grains gravitating down the cylinder and being discharged over the chute 65 located at the rear end of the machine while those lodged and caught in the nap of the lining will be thrown into the lower chute 66 and discharged out the front end of the machine.

What I claim as my invention is:—

In a grain separating machine, a supporting frame, a pair of upper similarly inclined cylindrical drums rotatably supported from the frame and arranged side by side and both having a lining presenting considerable nap, a hopper overlying the upper ends of the drums, feed chutes leading from the hopper into the ends of the drums, a centrally located rotatably mounted oppositely inclining drum underlying the former drums and rotatably carried by the frame, said latter drum having a lining presenting considerable nap, means for collecting grain discharging from the lower ends of the upper drums and delivering the same into the upper end of the 130

- lower drum, means for simultaneously rotating the drums, similar grain collecting and discharge chutes extending longitudinally of the drums, means supporting the rear ends of
5 the upper chutes and the front end of the lower chute from the frame for oscillatory movement, a vertical spindle rotatably mounted centrally on the rear end of the frame between the adjacent projecting ends
10 of the upper chutes, a horizontally disposed cross arm secured to the spindle and having the extending ends thereof overlying and swivelly attached to the adjacent ends of the chutes, a further vertically disposed spindle
15 rotatably carried by the rear end of the frame and located to the side of the adjacent projecting end of the lower chute, a crank arm extending from the latter spindle and overlying and pivotally attached to the latter
20 end of the latter chute, cranks secured to the adjacent ends of the spindles, a link pivotally connecting the latter cranks, a crank secured to the upper end of the central spindle, means for oscillating the latter crank to simultaneously reciprocate the shoes and a scraper
25 carried by the frame and extending longitudinally of each drum and contacting with the lining thereof in a location overlying the chutes.
- 30 Signed at Town of Birtle in Manitoba this
6th day of February, 1928.
